CORE CATCHER

Reid B. Grainger, Redondo Beach, Calif., assignor to Elliott Core Drilling Company, a corporation of California

Application December 11, 1937, Serial No. 179,307

3 Claims. (Cl. 255—72)

This invention relates generally to core drills for use in removing a core from the hole being drilled in earth formations. More particularly the invention relates to means associated with a 5 core barrel for retaining the core in the barrel during the removal of the core drilling apparatus and the core from the hole.

It is the usual practice in connection with core barrels to use core catching or retaining means at 10 the lower end of the core barrel in the form of spring fingers or in the form of dogs yieldably held inwardly in the path of the core by spring means. The core catching means is mounted at 15 the lower end of the inner core barrel and is designed to break off the core and retain it in the core barrel when the apparatus is pulled from the hole.

Where spring fingers are used for this purpose they are often ineffective on hard formations because they fail to dig into the core and break it off so as to retain the core in the barrel when the core barrel is lifted. This failure is principally due to the fact that the entering core 20 presses the spring fingers back against the inner wall of the core barrel and when the core barrel is subsequently raised the fingers, by reason of 25 their length and disposition adjacent the inner wall of the barrel, have a low angle of entrance or engagement with the core, and hence fail to 30 dig into the core, very often permitting the core barrel to be pulled over the core as the spring fingers slide along the sides thereof, thereby resulting in loss of the core. Furthermore, if the 35 core is taken from a hard formation very often the spring fingers will break off and therefore become ineffective for accomplishing the desired purpose.

It is therefore an object of this invention to 40 provide means for positively engaging the core to break off the core and hold it in position within the core barrel when the barrel is raised. In accomplishing this object it is a further object of 45 this invention to provide dog means for engaging the core which have a high angle of entrance into the core.

Where shorter dogs are used these are usually 50 yieldably held in position to engage the core and extend inwardly of the core barrel. When the core enters it forces these dogs back against the 55 walls of the inner core barrel against the force of the springs and often damages the core, especially if the core is taken in soft formation. Usually the springs are ineffective to force the dogs into the core when the core has been taken from hard formation and the dogs fail to dig into the core

and break it off and hold it within the core barrel when the core barrel is raised.

It is therefore an object of this invention to provide a core catching means which will not mar or scarify the entering core or tend to break it up and in accomplishing this object it is the purpose of this invention to provide dogs which are normally yieldably held in a retracted position out of engagement with the core. Furthermore, it is an object of this invention to provide means for positively forcing the dogs into engagement with the core when the core barrel is raised.

These and other objects will be apparent from the drawing and the following description thereof. Referring to the drawing, which is for illustrative purposes only,

Fig. 1 is a fragmentary sectional elevation of the lower end of a core drill showing the invention mounted at the lower end of the core barrel.

Fig. 2 is an enlarged fragmentary sectional elevation of the device of Fig. 1 showing details in the construction.

Fig. 3 is a sectional elevation on the same plane as Fig. 2 but showing a core in the barrel engaged by the core catching means of this invention; and

Fig. 4 is an inverted sectional plan view on line 4—4 of Fig. 3.

Particularly describing the invention, reference numeral 11 indicates the lower end of a drill collar 30 to which is threadably attached an ordinary fish-tail drill bit 12. The bit 12 is of the ordinary construction and is provided with an annular shoulder 13 which is designed to accommodate the lower end of the core barrel. This invention has 35 been shown in connection with the so-called wire line core barrels, that is, the type wherein the core barrel 14 is dropped down the hole when it is desired to take a core and it comes to rest in the position shown, the barrel subsequently being 40 raised by means of a wire line dropped into the hole and engaging the upper end of the barrel. However, the invention might be used in other types of core drills and is not limited in scope 45 to the particular type of coring apparatus shown in the drawing.

The inner core barrel 14 has threadably attached to its lower end the core catching means generally indicated by reference numeral 15. Referring to Figures 2 to 4 for the details in the 50 construction of the core catching means, this means comprises the tubular member 16 threadably attached to the lower end of the core barrel 14 and which is adapted to rest upon the shoulder 13 of the bit. The member 16 is provided with 55

lateral openings 17 in which are mounted core catching dogs 18 on the pins 16. These pins are secured in the bores 20 in any suitable manner. Each of the dogs is provided with a spring 22 which serves to yieldably hold the dog against the upper portion of the opening 17 in retracted position.

For the purpose of forcing the dogs 18 into engagement with the core, a core engaging member, generally indicated by reference numeral 25, is provided. This core engaging member is shown as a core catcher of the ordinary spring finger type, although any member capable of yieldably engaging the core might be used. Member 25 comprises a cylindrical body member 26 in which are mounted the upwardly and inwardly extending spring fingers 27. The lower end 26' of this member is rounded, as shown. The core engaging member 25 is slidably mounted within the member 16 and the lower rounded end 26' is adapted to engage the curved surfaces 18' of the dogs 18.

Referring to Fig. 3 for the operation of the device, it can be seen that when a core, generally indicated by 30, enters the core barrel and it is desired to remove the inner core barrel retaining the core 30 in place therein, the initial upward movement of the core barrel 14 and its attached core catching means 15 causes the spring fingers 27 to tend to dig into the core. These spring fingers engage the core sufficiently to cause relative downward movement of the core engaging member 25, thereby forcing the dogs 18 out into engagement with the core as shown in Fig. 3, the lower rounded end 26' of the cylindrical body member 26 acting as a cam on the rounded surfaces 18' of the dogs 18. The dogs, by reason of their relatively short length, readily dig or bite into the core, entering the same at a high or relatively great angle. Further upward movement of the core barrel causes these dogs to break the core, as indicated in Fig. 3, and retain it within the core barrel when the same is raised in the hole.

It should be apparent from this description that with this construction soft cores will not be damaged by reason of the fact that the dogs 18 are held out of engaged position with the entering core. It should also be apparent that a positive means is provided for breaking off and retaining hard cores by reason of the fact that the spring fingers 27 upon the member 26 sufficiently frictionally engage the core when the barrel is raised so as to cause relative downward movement of the member 26 to the mem-

ber 16 and thereby serve to actuate and force the dogs 18 out into engagement with the core, whereby they become effective to break off the core and retain it within the core barrel.

I claim as my invention:

1. For use in combination with a core barrel, core catching means comprising: a tubular member mounted on the lower end of the core barrel; core catching dogs pivotally mounted in said tubular member; spring means for yieldably holding said dogs in a retracted position; a core engaging member slidably mounted in said tubular member and adapted to engage said dogs, said core engaging member being adapted to force said dogs to a core engaging position 15 when said core barrel is raised with a core therein.

2. For use in combination with a core barrel, core catching means comprising: a tubular member having lateral openings in its wall 20 mounted on the lower end of the core barrel; core catching dogs mounted on said tubular member in said openings therein, said dogs extending inwardly of the inner surface of the tubular member; spring means yieldably holding said dogs in retracted position; a core engaging member slidably mounted in said tubular member and having a lower cylindrical portion bearing upon said dogs, said core engaging member being adapted to force said dogs into a core 30 engaging position when said core barrel is raised with a core therein.

3. For use in combination with a core barrel, core catching means comprising: a tubular member mounted on the lower end of the core 35 barrel, said member being provided with lateral openings; pin means extending across each of said openings; a core catching dog mounted on the respective pin means in each of said openings; spring means associated with each of said 40 dogs for yieldably holding them in a retracted position whereby the core engaging ends of said dogs extend inwardly only a limited distance beyond the inner surface of said tubular member; a core engaging member slidably mounted in 45 said tubular member, said core engaging member comprising a lower cylindrical base portion provided with a bevelled lower edge for engaging said dogs and an upper spring portion for engaging a core within said core barrel, said 50 core engaging member being adapted to force said dogs into a core engaging position upon upward movement of said core barrel with a core therein.
